UNITED STATES PATENT OFFICE.

EDWARD C. HOLMES, OF CINCINNATI, OHIO.

HOLDER FOR DRILLING MECHANISM.

Application filed September 8, 1925. Serial No. 54,884.

My invention relates to holders for electric and pneumatic drills and particularly to holders which are provided with spider arms extending from the bodies of the drills 5 or the like for the manual transportation and alignment in use.

In my copending application Serial No. 43,985, of July 16th, 1925, to which reference is hereby made, I have described a carriage 10 for drills which are particularly adapted to drive screw spikes such as are provided in my Patent No. 1,294,268 and in my copending application Serial No. 29,212 of May 9, 1925.

15 It is my object in the invention herein disclosed to provide a manually movable holder which is adapted to support a drill, and which will provide means for aligning a drill so as to drive a screw spike on either 20 side of a rail or other structure which is adapted to be secured with a screw spike.

It is my object in such a holder to provide a manually movable device which shall be adapted for use in minor repairs of such 25 variable character as to not require the larger carriage as described in my copending application.

Referring to the drawing in which I have shown a preferred type of holder:

30 Figure 1 is an end elevation of the holder.

Figure 2 is a side elevation of the holder.

Figure 3 is a plan view of one of the holder arms and a portion of the base supporting the holder.

35 It should be noted that the holder is specially adapted to guide and support an electric or pneumatic drill from which two sideways extending spider arms furnish a manual means of moving and operating the 40 mechanism. As such mechanisms are common in the art and as my structure is adapted for use with any type from which spider arms extend from opposite sides no showing has been made of such a drill.

45 Generally indicated at 1 is a flat elongated plate which is adapted to rest on a rail which is to be secured to tie plates or cross ties in ordinary track construction. In the illustration I have shown the plate as 50 having close to each end a boss 2 and a raised extension 3 for a purpose which will be hereinafter described. The bosses are provided with holes 4 into which studs 5 or other pivotal means may be secured. The holder 55 is provided with upright extending members 6 having a rounded groove 7 in the ex-

act center of the highest part of the upright.

The upright members extend sideways in alignment with the length of the groove 7 and each side portion is provided with an 60 elongated slot 8 of slightly wider extent than the spider arms of a drill will require to fit snugly. In the illustration I have shown two of the upright members pivotally mounted in the bosses in the base plate. Although four uprights might be required it is my purpose to completely disclose a structure comprising two uprights and it will be understood that the addition of more than two uprights operable in a similar manner 70 is still within the range of my invention.

The elongated slots are disposed in alignment so that by tightening down the studs 5, mounting the base in alignment with a rail and having the uprights disposed at the 75 same angle to the rail the center of the slots will extend an equal distance on each side of the rail from its center.

When the holder is used for rails of different sizes it will be obvious that by releasing the studs 5 and swivelling the upright to either side that the distance from the center of the rail of the slots 8 may be readily controlled and the uprights conveniently set at whatever angle to the rail will provide a 80 position for the drill directly over the position in which a spike is to be screwed to secure the rail to the cross tie.

85 In a foregoing paragraph I have noted that the width of the slots is slightly larger than would be required to provide a snug fit for spider arms of a drill. The purpose of such a construction is to provide sufficient clearance to allow the drill arms to move up and down in the slots, when the uprights are 90 at an angle to the rail.

95 For aligning the base member on the rail I have provided pivoted lugs 9 mounted under the raised extensions 3 which have downwardly extending ends 10 which may be secured at a desired angle with the rail on which the holder rests so that the clamping 100 arms may be adjustably swivelled to form guides for the holder which will align it and snugly fit the sides of the head of the rail to 105 prevent the holder from rocking out of alignment.

110 From the base of each side of the uprights adjacent their lower ends I have provided stabilizer arms 11 which are mounted in the uprights and which extend down below the base on each side. The preferable mount-

ing may be provided with stud bolts 12 so that by loosening the bolts the stabilizer arms may be adjusted in desired position so that their ends will extend down and lie alongside of the base of the rail which is shown in section at 13. The stabilizer arms may be provided with slots 14 which fit over the upper corners of the base of the rail and these arms serve to not only align the holder but also to prevent its tipping over on the rail.

In order to provide for a snug fit of the spider arms to the drill within the slots 8 I have found that by rounding the sides of 15 the slots as shown at 15, the spider arms will have less tendency to bind when being moved up and down in the slots.

The operation of the holder to guide a drill with spider arms with which screw threaded spikes are to be secured, may be 20 readily understood by reference to Figure 1. The drill when not in use may be disposed with a spider arm resting in each of the top grooves 7. When a spike is to be screwed 25 into one or the other side of a tie to secure a rail, a spike is put in the chuck of the drill and the drill is lifted from the grooves 7 and placed in the slot on whichever side the spike 30 is to be secured. The depth of the slots will be only enough to allow the chuck to screw in the spike so that there will be no danger of over-screwing the spike and ruining the 35 drill, as would occur if the downward movement of the drill were not controlled and the drill was to be merely held in the hands.

The position of the spike on one side of the rail being determined it will be readily observed that by lifting the drill from the slot 40 on one side of the holder and inserting it in the slot on the other side of the holder the position of the spike will be exactly opposite the first mentioned spike which is usually 45 the proper position.

The weight of such a holder will be great, 50 so to lighten the weight without sacrificing strength I have reinforced the uprights with webs 16 and provided a central aperture 17 in the holder which furnishes a convenient hand hole at the top with which the holder 55 may be lifted from a rail and moved to some other position.

Having thus described my invention, what I claim as new and desire to secure by Letters Patent, is:—

55 1. A holder for screw spike driving mechanism comprising in combination a base member adapted to support the holder, swivelling uprights with means for detachably securing the uprights in the base member 60 and a pair of opposed elongated slots in the uprights adapted to guide spider arms of the driving mechanism, and means for aligning said base member on a rail, and means extended from the uprights adapted 65 to prevent tilting of the holder.

2. A support for mechanism for driving screw threaded spikes having oppositely extended spider arms, comprising a holder adapted to align said arms in a downward movement of the mechanism, means for 70 aligning the holder on a rail, and means for adjusting the position of the aligning means for the arms with relation to the aligning means for the holder.

3. A support for mechanism for driving 75 screw threaded spikes having oppositely extended spider arms, comprising a holder adapted to align said arms in a downward movement of the mechanism, means for aligning the holder on a rail, and means 80 for adjusting the position of the aligning means for the arms with relation to the aligning means for the holder, and stabilizing means adjustably mounted in the holder adapted to support the holder from the base 85 of a rail.

4. A support for a drill for driving screw spikes comprising a pair of interspaced arms having elongated slots therein with beveled sides, said slots disposed on each side equidistant from the center of the arms, a supporting base plate, means for aligning the base plate on a rail, a pivotal mounting for the arms in the base plate, and the central portion of said arms cut away to provide 90 hand holes for transporting the holder.

5. A rail bracket for guiding a tool having a pair of handles by which said tool is supported comprising a pair of substantially similar adjustably mounted plural guides 100 each having guiding portions adapted to extend in substantially vertical planes on each side of a rail, and the guiding portions adapted to receive the handles of the tool.

6. A rail bracket for guiding a tool having a pair of handles by which said tool is supported comprising a pair of substantially similar adjustably mounted plural guides each having guiding portions adapted to extend in substantially vertical planes on each 110 side of a rail, and said guiding portions consisting in uprights having slots therein which are adapted to receive the handles of the tool.

7. A rail bracket for guiding a tool having a pair of handles by which said tool is supported comprising a pair of substantially similar adjustably mounted plural guides each having guiding portions adapted to extend in substantially vertical planes on each 115 side of a rail, the guiding portions adapted to receive the handles of the tool, said bracket provided with adjustable means for aligning the bracket on a rail.

8. A rail bracket for guiding a tool having a pair of handles by which said tool is supported comprising a pair of substantially similar adjustably mounted plural guides each having guiding portions adapted to extend in substantially vertical planes on 125 130

each side of a rail, the guiding portions adapted to receive the handles of the tool, said bracket provided with adjustable means for aligning the bracket on rails having heads of different widths.

9. A rail bracket for guiding a tool having a pair of handles by which said tool is supported comprising a pair of substantially similar adjustably mounted plural guides each having guiding portions adapted to extend in substantially vertical planes on each side of a rail, the guiding portions adapted to receive the handles of the tool, said bracket provided with adjustable means for aligning the bracket on rails having heads of different widths, and said bracket having adjustable anti-tilting devices for aligning

the bracket of rails having bases of different widths.

10. A support for mechanism for driving screw threaded spikes having oppositely extended spider arms, comprising a pair of holders having vertically disposed elongated slots therein for vertically guiding arms of said mechanism, said holders having a base portion supporting them, pivoted clamps on the base adapted to align the holder on a rail, and means for adjustably regulating the position of the slotted portions with relation to the central longitudinal line of the base, said slotted portions being beveled convexly to admit said arms therein in more than one angle.

EDWARD C. HOLMES.
